UNITED STATES PATENT OFFICE

CARL C. REYNOLDS, OF SANTA FE, NEW MEXICO

LIQUID PURIFICATION SYSTEM

Application filed February 13, 1930. Serial No. 428,188.

The present invention relates to purifying systems and more particularly to a purifying system adapted for use in the clarification and purification of gasoline used in dry cleaning processes.

An object of this invention is to provide a purification system by which the liquid used in the cleaning process is in continuous motion throughout the system during the process 10 of cleaning.

Another object of this invention is to provide in a cleaning system, means by which the fluid may be kept in constant motion throughout the system and at the same time, 15 the liquid returning to the washer is not only clarified but reheated, the heating means being interposed in the return line so that a constant stream of warm fluid is forced into the washer.

20 A further object of this invention is to provide in a system of this character, means by which large particles of material removed in the cleaning of clothes or the like may be initially removed from the fluid before the fluid passes into the process of purification.

A still further object of this invention is to provide in combination with a purification system, means by which the cleaned fluid may be properly stored in a reservoir or 25 container so positioned as to meet any of the local requirements as to the storage of inflammable liquids.

30 A further object of this invention is to provide visible means by which the quality of the fluid may be determined as it is passing through the system.

Another object of this invention is to provide in a system of this character, means by which the entire system may be thoroughly 40 and adequately drained, the draining means being connected to a sewer or the like and also means by which the inflammable or cleaning fluid may be withdrawn from the component parts of the system and placed in a reservoir or storage tank where it will be ready for use when desired.

The above and various other objects and advantages of this invention will in part be described in and in part be understood from the following detailed description of the

present preferred embodiment, the same being illustrated in the accompanying drawings wherein:—

Figure 1 is a fragmentary detailed side elevation partly in section of a device constructed according to the preferred embodiment of this invention; 55

Figure 2 is a fragmentary side elevation partly in section of the device; and

Figure 3 is a longitudinal section taken 60 through the presfiltering member.

Referring to the drawings wherein like numerals of reference designate corresponding parts throughout the several views, the numeral 10 designates a washer of conventional type which is used in the cleaning of cloth or the like and preferably a washer which is adapted for use in holding gasoline for cleaning clothes by what is commonly called the "dry cleaning process". The washer 10 is provided with an inlet 11 and an outlet 12 by which the cleaning fluid may be placed into the washer and drained therefrom. The outlet 12 is connected by means of a pipe 13 to a storage tank 14 which is positioned remote from the washer and preferably positioned underground so as to comply with the usual regulations as to storage of inflammable liquids in an underground storage or reservoir. 70

A pump or pressure means 15 is interposed in the pipe line 13 between the washer 10 and the storage tank 14 and a valve member 16 is positioned in the line 13 intermediate the washer 10 and the pump 15. A second valve member 17 is mounted in the pipe line 13 between the pump 15 and the storage tank 14 so that when the pump 15 is operating, the fluid may be either withdrawn 85 from the storage tank or from the washer. 90

A pipe line 18 is connected to the pump 15 at one end and at the opposite end is connected to the storage tank 14 being adapted for use in returning the fluid to the tank 14 when it is withdrawn from the cleaning system. 95

A clarifying or initial cleaning member 19 is connected by means of a pipe 20 to the pipe line 18 and a valve member 21 is mounted in the pipe line 18 in a position where the 100

storage tank or reservoir 14 may be cut off from the pipe line 18, and the fluid moving in the pipe line 18 forced into the pipe line 20. The pipe line 20 preferably extends through the top portion of the clarifying or cleaning member 19 and terminates adjacent the bottom thereof.

The clarifying member 19 is adapted to contain a cleaning compound which may be of any conventional character such as caustic soda, or the like or a combination of cleaning members, and the end of the pipe 20 terminates within the cleaning fluid 22 which is positioned in the bottom of the cleaning member 19. If desired, the bottom portion of the cleaning member 19 may be constructed in the shape of a cone or the like and the quantity of cleaning fluid within the member 19 may be varied according to the needs of the system. The cleaning member 19 is provided with an outlet 23 at the top thereof and a pipe line 24 leads from the outlet 23 to a rinsing or second cleaning tank or member 25, the pipe line 24 entering the second cleaning tank in the bottom thereof as at 26. The first cleaning tank or initial clarifying member 19 is preferably mounted in an elevated position on suitable support members 27 and is preferably considerably larger in diameter than the rinsing tank 25 but of substantially less height, being from one-third to one-half as high as tank 25. The top or outlet 23 of the clarifying member 19 is preferably positioned somewhat higher than the top of the rinsing tank 25 so that when the clarifying tank 19 is filled, the fluid therein will flow by gravity into the rinsing tank 25 where it is desired to use pressure to force the liquid through the system; the various tanks embodied in this system may be positioned with their bottom portions substantially in alignment with each other.

A valve member 28 may be interposed in the pipe line 24 adjacent the intake portion of the rinsing tank 25 so that, when desired, the pipe line 24 may be closed.

The rinsing tank 25 is adapted to contain water or any other desired cleaning compound and is preferably of a configuration somewhat similar to the first clarifying member 19 having the bottom thereof in cone shape construction with the apex extending downwardly and the quantity of cleaning compound 29 in the rinsing tank 25 may be varied to suit the needs of the system. Preferably the rinsing tank 25 is of greater height than the tank 19 and of less diameter.

The cleaning member 29 in the rinsing tank is adapted to further clean the gasoline coming from the clarifying member 19 and is particularly adapted to remove any of the cleaning compound or dirt particles which may pass outwardly from the clarifying member 19. The compounds 22 and 29 are preferably of a heavier composition than

gasoline so that when the gasoline is forced into the containers the cleaning compounds will at all times be disposed in the bottom of the containers.

The pipe line 24 may be provided with an air vent valve 30 adjacent the outlet 23 so that when it is desired to empty the tanks, the vent valve may be opened so as to permit air to enter the tank and facilitate removal of the fluids therein by gravity and conversely, when it is desired to fill the tanks the valves may be opened so as to remove the air from the system.

The rinsing tank 25 is provided with an outlet 31 in the top portion thereof and a pipe line 32 leads from the outlet 31 to a filtering member 33, the pipe line 32 being connected to the filtering member 33 at the intake portion 34 thereof. The filtering member 33 may be of any desired construction which is adapted to filter the gasoline after it has passed outwardly from the rinsing tank and is preferably constructed with a tortuous passage 35 through which the gasoline must pass before entering the outlet 36. The outlet 36 is connected by a pipe line 37 to the inlet pipe 11 of the washer member 10 thereby completing the circuit from the outlet 12 of the washer through the clarifying system and back into the inlet 11 of the washer. The rinsing tank 25 may be provided with an air vent valve member 30 which may be similar to the construction of the air vent valve 30 on the clarifying tank and is adapted to be used for the same purpose, namely, to permit proper draining of the tank 25 and conversely to facilitate filling of the tank so as to remove all of the air therefrom.

The filtering member 33 is preferably of somewhat smaller construction than the rinsing tank 25 and the top or outlet portion 36 of the filtering member 33 is preferably positioned in a lower plane than the outlet 31 of the rinsing tank so that the fluid in the line 32 will flow by gravity into the inlet 34 and out of the filtering member outlet 36 into the intake pipe line 11.

The dirty fluid which is withdrawn from the washer 10 through the outlet 12 frequently contains a number of solid articles such as buttons, pieces of cloth or the like and in order to prevent clogging or the free passage of the fluid in the clarifying system, a trap 38 is interposed in the pipe line 13 intermediate the outlet 12 and the pump member 15. The trap member 38 may be of any desired construction but is preferably provided with a tortuous passageway in which may be mounted screen members 39 and, if desired, the initial or pre-cleaning of the fluid may be facilitated by placing cotton seed hulls 40 or any other desired cleaning members or compound within the trap 38.

The fluid which is used in the washing or cleaning process is preferably heated and in

order to obtain the proper temperature of the fluid, a heating member 41 is interposed in the return line 32 intermediate the rinsing tank 25 and the filtering member 33. The heating member 41 is preferably constructed in the form of a conventional jacket or pipe encircling member which is provided with an intake 42 and an outlet 43 connected to a suitable source of steam or other heating member. While I have disclosed a heating member receiving heat from a steam line, I do not wish to be understood as being limited to the use of steam for heating the fluid passing through the return line 32 as any other form of a heating member may be used such as electricity or the like.

Where the system herein disclosed is used for a comparatively small or medium sized washing plant, the use of a single clarifying tank 19, a rinsing tank 25 and a filtering member 33 will be found adequate to properly clean all of the gasoline or other cleaning fluid which is necessary for a plurality of washing members 10. However, where an exceedingly large number of washing machines are used, the capacity of the cleaning system may be increased by adding another clarifying tank 44 which is connected by an intake line 45 to the pipe line 18 and is of similar construction to the clarifying tank 19. The intake line 45, as in the clarifying tank 19, terminates adjacent the bottom of the tank 44, and the tank 44 is provided with a cleaning compound 46 which may be similar to the cleaning compound 22 or, if desired, a separate and entirely distinct cleaning compound may be used.

A valve member 47 is positioned in the pipe line 18 intermediate the pipe line 45 and the pipe line 20 so that the fluid moving forwardly in the pipe line 18 may be forced downwardly into the clarifying tank 44. The tank 44 is provided at the top portion thereof with an outlet 48, and the pipe line 20 is extended downwardly from the pipe line 18 and connects with the outlet 48 of the initial clarifying tank 44.

A valve member 49 may be interposed in the pipe line 20 intermediate the pipe line 18 and the outlet 48, and another valve 50 may be positioned in the intake pipe line 45 spaced downwardly from the pipe line 18 so that, if desired, the valves 50 and 49 may be closed and the valve member 47 opened, thereby cutting off the first cleaning tank 44 and permitting the fluid to pass upwardly into the clarifying tank 19.

In the operation of this cleaning or purification system, the pumping member 15 may be operated in any conventional manner as by a motor or the like, and where it is desired to fill the tanks 19 and 44 with the desired cleaning fluid, the desired compounds in the proportions required may be placed into a mixing tank 51 or the like which may be open

at the top or provided with a suitable inlet portion 52 and provided with an outlet 53 at the bottom thereof. The mixing tank 51 may be relatively small in view of the fact that a relatively small quantity of cleaning fluid is normally placed into the clarifying tanks 19 and 44 but will, of course, be of sufficient capacity to contain fluid for at least one filling of the tanks 19 and 44 but may be of larger capacity so that a reserve quantity of cleaning fluid may be maintained on hand.

The mixing tank 51 is connected by a pipe line 54 to the pipe line 18, and a valve member 55 is interposed in the pipe line 54 intermediate the mixing tank and the pipe line 18 so that the pipe line 54 may be opened or closed as desired.

When it is desired to place the cleaning fluid into the clarifying tanks 19 and 44 the valve member 16 may be closed and the valve 17 opened, thereby permitting the suction pump 15 to withdraw the fluid from the line 13.

A valve 56 is mounted in the line 13 intermediate the mixing tank 51 and the storage tank 14 and is adapted to close the line 13 leading to the storage tank so that when the valve 55 is opened, the pump 15 will withdraw the cleaning fluid from the mixing tank 51 and force it through the pipe line 18.

The valve 47 in the pipe line 18 may be closed and the valve 50 opened, thereby permitting the fluid to pass downwardly into the tank 44 and when the desired quantity of cleaning fluid has entered the tank 44 the valve 49 may be closed and the valve 50 may be closed and the valve 47 opened, it, of course, being understood that during this process the valve 21 is maintained closed.

When the valve 47 is opened, the fluid will pass upwardly through the pipe line 20 and downwardly into the fluid cleaning member 19. In order to determine the quantity of cleaning fluid being placed into the cleaning tanks 44 and 19, a vision glass 57 may be mounted in a pair of parallel spaced pipe members 58 which are connected to the tank members 19 and 44 adjacent the bottom thereof, the vision glass or member 57 being of conventional tubular construction.

In order to place the desired quantity of rinsing compound 29 in the rinsing tank 25, the valve member 55 may be closed thereby shutting off the mixing tank 51, and the valve 17 may be closed. A pipe line 59 may be connected to the pipe line 13 intermediate the valve members 16 and 17 and connected to a source of water supply or the like. A valve 60 is preferably positioned in the water pipe 59 and when it is desired to fill the rinsing tank 25 with the desired quantity of water, the valve 60 may be opened permitting the water to pass through the pump 15 and into the pipe line 18.

A valve 61 is mounted in the pipe line 18 adjacent the rinsing tank and intermediate the valve 47 and the pump 15. A pipe line 62 is connected at one end to the pipe line 18 intermediate the valve 61 and the pump 15 and at the opposite end is connected to the outlet pipe line 32. A valve 63 is positioned in the pipe line 32 intermediate the pipe 62 and the heater 41. The valve 61 may be closed thereby forcing the water upwardly through the pipe line 62 and into the outlet 31 of the rinsing tank 25, the vent valve 30 being of course closed and the valve 63 is closed so as to prevent escape of the water through the valve.

If desired, a vision glass 64 may be connected by pipe lines 65 to the rinsing tank 25 adjacent the bottom thereof so that the quantity of water placed in the tank may be readily visible.

When the desired quantity of water 29 has been placed in the rinsing tank 25, the valve 60 may be closed and the valve 61 opened, likewise the valves 17 and 56 may be opened, permitting the pump 15 to withdraw the gasoline from the storage tank 14. The gasoline from the storage tank will pass through the pump and into the pipe line 18, and in the smaller system the gasoline will enter the pipe line 20 and pass downwardly into the first clarifying member 19, it of course being understood that the valve 21 is maintained closed during this process.

The gasoline passing downwardly into the clarifying tank 19 will bubble upwardly through the cleaning fluid 22 and when the tank 19 has been filled the gasoline will pass outwardly through the outlet 23 and the pipe 24 into the tank 25, the valve 28 being of course opened. The gasoline will bubble up or pass upwardly through the rinsing compound 29, and when the tank 25 has been filled the fluid will pass outwardly through the outlet 31 and into the return line 32.

A valve 66 is mounted in the pipe line 62 intermediate the lines 32 and 18 so that the gasoline passing through the line 32 and returning to the washer will not return to the pipe line 18. The gasoline will gravitate through the pipe 32 past the heating member 41 and into the filtering member 33. The filtering member 33 will then be filled and the gasoline will pass outwardly through the outlet 36 and the pipe 37 into the return or intake line 11. If desired, a visible glass member 67 may be interposed in the return line 37 so that the quality of the gasoline may be readily visible.

When the entire system has been filled with gasoline, the valve 17 may be closed thereby stopping the pumping of gasoline from the storage tank 14, and the valve 16 opened thereby forming a continuous and endless passageway from the washer through the pump and into the clarifying or cleaning members.

After the system has been in use for a period of time, it will be desirable that it be cleaned out, and in order to accomplish this a draining connection 68 is connected to the cleaning member 19 and the pipe line 20, the connection 68 being positioned on the tank 19 at a point spaced upwardly from the cleaning fluid 22 so that the gasoline may be withdrawn therefrom.

Through the use of the draining connections 68 and 70 the liquid in the tanks 19 and 25 may be drained out therefrom without removing the cleaning compound 22 and 29, the drained fluid flowing by gravity into the pipe 18 and the reservoir 14 so that where local conditions require the draining of inflammable fluid from tanks of this kind, the fluid may be readily drained and stored in the reservoir which is preferably positioned under ground.

A valve 69 may be interposed in the connection 68 intermediate the tank 19 and the line 20 so as to control the draining of the fluid. The rinsing tank 25 may be provided with a draining connection 70 which is connected at one end to the rinsing tank spaced upwardly from the bottom thereof and at the other end to the pipe 62 intermediate the valve 66 and the pipe 18. A valve 71 is interposed intermediate the opposite ends thereof so that when desired, the gasoline may be drained, it of course being understood that the connection 70 is mounted in the tank at a point approximately level with the water or cleaning member 29.

The clarifying member 19 and the rinsing tank 25 may also be provided with a second draining connection 72 which is connected to a suitable source of draining such as a sewer or the like. A valve 73 may be interposed in the connection 72 so as to control the draining of the tank. The filtering member 33 may also be provided with a draining connection 74 which is connected at one end to the bottom of the filtering tank 33 and at the opposite end to the pipe line 13, it of course being understood that the filtering member 33 will contain only gasoline and this gasoline may be returned to the storage tank 14.

A valve 75 is interposed in the connection 74 intermediate the filtering tank 33 and the pipe line 13 so as to permit the gasoline to be drained when desired. A valve member 76 may be positioned in the pipe line 37 intermediate the intake 11 and the outlet 36 of the filtering member 33 so as to stop the flow of gasoline to the washer when desired.

In the modification of this device, where a clarifying tank 44 is interposed in the system, a connection 77 is connected at one end to the pipe line 13 and at the opposite end to the intake pipe 45 intermediate the valve 50 and the top of the tank. A valve member 78 may

be positioned in the connection 77 so as to control the passage of fluid through the connection. A valve member 79 may also be interposed in the pipe 13 intermediate the tank 14 and the connection 77 so that when it is desired to withdraw the fluid from the clarifying tank 44, the valve 79 may be closed thereby shutting off the suction from the storage tank and permitting the pump 15 to withdraw the fluid from the tank 44.

It will, of course, be understood that various changes and modifications may be made in the details of construction and design of the above specifically described embodiment of this invention and that various changes and modifications in the component parts of the system may be made, and that the component parts thereof may be made in various sizes and configurations depending only upon the capacity of the cleaning plant wherein the system is adapted to be installed, such changes and modifications being limited only by the scope of the following claims:—

What is claimed is:—

1. A purifying system of the character described comprising in combination with washing means, a reservoir, a relatively large cleaning tank, a rinsing tank substantially smaller but of greater height than said cleaning tank and positioned in a plane below said cleaning tank, a filter member substantially smaller than said rinsing tank and mounted in a plane below said rinsing tank, connecting means adapted to connect said cleaning tank with said rinsing tank, connecting means adapted to connect said reservoir, cleaning tank, rinsing tank and filtering member with said washer whereby to provide a passage permitting the liquid to gravitate toward said washer, draining means secured to each of said tanks whereby to permit the draining thereof to the reservoir, heating means engaging said connecting means and adapted to raise the temperature of the liquid within said connecting means, normally closed vents for each of said tanks and a second connecting means connecting said washer and said cleaning tank whereby to provide a passageway for oppositely directed liquid, and a pump interposed in said latter connecting means, said pump being adapted to withdraw the liquid from said washer and coercively force the liquid into said cleaning tank.

2. A liquid purifying system of the character described comprising in combination with washing means, a plurality of tank members mounted in spaced relation to each other, connecting means for said tank members and said washing means, said tank members being mounted in stepped relation to each other whereby to permit the liquid to gravitate from one tank to another and to said washing means, storage means, means for connecting said storage means to said tanks, drains se-

cured to each of said tank members and said connecting means for returning the liquid to said storage means, liquid purifying means mounted in said tanks, filtering means interposed between said tanks and said washing means, heating means whereby to heat the liquid gravitating from said tanks, cleaning fluid mixing means connected to said tanks, normally closed vents for each of said tank members and pump means connected to said tanks and said washing means whereby to provide a continuous flow of liquid to said tanks.

3. A liquid purifying system of the character described comprising in combination with washing means having an inlet and an outlet, a plurality of liquid cleaning members arranged in stepped relation to each other, pipe means connecting said cleaning members together and with said inlet of said washing means, transparent means interposed in said connecting means, heating means engaging said connecting means whereby to heat the liquid passing through said connecting means, connecting means connecting said outlet of said washing means with said cleaning members, pump means interposed in said latter connecting means and adapted to force the liquid therethrough, a liquid reservoir connected to said latter connecting means, drain means for said cleaning members and connected to said pipe means whereby to drain the liquid therefrom into the reservoir, and normally closed vents for each of said cleaning members.

In testimony whereof I hereunto affix my signature.

CARL C. REYNOLDS.
